UNITED STATES PATENT OFFICE

95,215

DESIGN FOR A LOLLIPOP

Anthony Barone and Alphonso Bove,
New Haven, Conn.

Application January 30, 1935, Serial No. 55,155

Term of patent 3½ years

To all whom it may concern:

Be it known that we, Anthony Barone and Alphonso Bove, citizens of the United States, residing at New Haven, in the county of New Haven and State of Connecticut, have invented a new, original, and ornamental Design for a Lollipop, of which the following is a specification, reference being had to the accompanying drawing, forming part thereof.

The figure is a perspective view of a lollipop showing our new design.

We claim:

The ornamental design for a lollipop substantially as shown.

ANTHONY BARONE.
ALPHONSO BOVE.
